BOTTLE CAP

Filed Jan. 14, 1925

FIG. 1

FIG. 2

FIG. 3

Inventor
F. V. Lindsey
Ex

UNITED STATES PATENT OFFICE.

FLORIAN V. LINDSEY, OF WINNIPEG, MANITOBA, CANADA.

BOTTLE CAP.

Application filed January 14, 1925. Serial No. 2,359.

The invention relates to improvements in a bottle cap particularly adapted for use on milk, cream or other such like bottles and an object of the invention is to provide a 5 simply constructed, inexpensive and durable cap which can be readily attached to the bottle or removed therefrom and which is provided with a gate which can be opened and closed as occasion demands to permit of 10 the pouring of the liquid or of the sealing of the bottle to prevent dirt, flies and such like foreign matter from entering the bottle through the neck.

With the above objects in view the invention 15 consists essentially in the arrangement and construction of parts hereinafter more particularly described, reference being had to the accompanying drawing in which:

Fig. 1 is a perspective view of the bottle 20 cap applied on the neck of the bottle and in the closed position.

Fig. 2 is a vertical sectional view through the device applied on the bottle.

Fig. 3 is an inverted perspective view of 25 the cap.

In the drawing like characters of reference indicate corresponding parts in the several figures.

The body 1 of the cap is in the form of 30 a metallic plate having a diameter slightly larger than the open end of the bottle neck 2.

Milk and cream bottles usually have their upper ends out-flared to provide a more or less semi-circular external rim 3 and they are 35 also provided with an internal ledge 4, the ledge being utilized as a seat for the customary circular cardboard cap (not shown). The diameter of the plate 1 is such that extends somewhat beyond the ledge so that it 40 effectively covers the bottle neck opening.

The plate 1 is supplied with a plurality of outstanding fingers 5 which when the cap is applied to the bottle are bent downwardly around the rim 3 to hold the cap in place.

Obviously by spreading these fingers outwardly one can readily remove the cap.

The body of the plate 1 has a substantially V-shaped or segmental portion thereof cut away to provide an outlet opening 6. A gate 50 7 is pivotally attached by a centrally posi-

tioned rivet 8 to the plate and this gate is of such a shape that when closed as shown in the drawings, it will close the opening 3. The gate underlies the plate and is fitted with an upstanding finger piece 9 which 55 when the gate is closed, is adapted to enter the notch 10 cut in the plate.

When it is desired to pour milk from a bottle equipped with this cap, it is only necessary to open the gate by swinging the 60 finger piece until it engages the opposite side of the opening 3 remote from the notch 10.

When the gate is closed, the edge thereof carrying the finger piece underlies the adjacent edge of the plate.

In the drawing I have shown a slight air space between the cap and the end of the bottle, such being equal to the thickness of the gate. This will effectively keep flies, 70 dust and so forth out of the bottle and will allow air to circulate. If it is desired, however, to tightly close the bottle it is only necessary to make the radius of the gate approximately equal to the radius of the 75 ledge 4. The gate will then operate in the ledge and the plate will seat tightly against the end of the bottle.

What I claim as my invention is:—

The combination with the neck of a bottle, 80 the upper end of the neck being provided with an outstanding rim, of a circular metallic cap normally overlying on the open end of the bottle neck and having a segmental portion thereof cut away to provide a pouring opening and provided further with a plurality of integrally formed downturned marginal resilient fingers adapted to close against the outer face of the rim and detachably hold the cap and a gate underlying the 85 cap and pivotally attached centrally to the cap and adapted to close the pouring opening and space the cap from the upper end of the neck to provide an air passage and provided further with an upstanding finger 90 piece adapted in the closed position of the gate to enter a notch provided in the cap.

Signed at Winnipeg, this 20th day of November, 1924.

FLORIAN V. LINDSEY.
